UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

THREAD-FINGER MECHANISM.

1,091,421.

Specification of Letters Patent. Patented Mar. 24, 1914.

Application filed September 29, 1908, Serial No. 455,332. Renewed January 16, 1914. Serial No. 612,570.

To all whom it may concern:

Be it known that I, HARRIE A. BALLARD, a citizen of the United States, residing at Boston, in the county of Suffolk and State 5 of Massachusetts, have invented certain new and useful Improvements in Thread-Finger Mechanism, of which the following is a specification.

This invention relates to shoe sewing machines and particularly to the stitch forming mechanism.

It has for its object to provide for a machine of this type a thread finger of simple construction, together with improved means 15 for mounting and actuating the same.

The function of the so-called thread finger is to engage the needle thread near the needle and draw off a certain quantity of thread from the supply prior to being drawn 20 through the work. The thread finger is so actuated as to first draw the thread as stated and to give off the thread so drawn at the instant when the needle draws back through the work. In other words it measures off 25 sufficient thread for each stitch and delivers it to the needle at a time when the supply thread is locked at another point.

One of the objects of the invention consists in forming the thread finger of a substantially straight rod having a hook at one 30 end.

Another object is to mount the rod so as to leave it accessible for adjustment or removal, and so as to reduce to a minimum the 35 friction of its engagement with its support or guide.

Referring to the drawings forming a part of this specification, Figure 1 represents a vertical section of a portion of a shoe sewing 40 machine including the thread finger mechanism. Fig. 2 represents parts of the stitch forming mechanism in another position. Fig. 3 represents a section on line 3—3 of Fig. 2. Fig. 4 represents a section on line 45 4—4 of Fig. 1. Fig. 5 represents a section on line 5—5 of Fig. 4.

The same reference characters indicate the same parts wherever they occur.

For the purpose of illustration, the thread 50 finger is shown in connection with a lock-stitch machine, but it may be equally adapted to other styles of shoe sewing machines.

On the drawing 10 represents a portion of the head or frame of the machine which is

provided with an oscillatory needle carrier 55 11 mounted upon a stud 12.

13 represents a main power shaft mounted in bearings in the head, and by which the several instrumentalities may be actuated, the means for oscillating the carrier 11 not 60 being shown.

14 represents a curved needle mounted in the carrier 11 and provided with a hook or barb 15 which is adapted to draw the thread *a* upwardly through a shoe sole *b* clamped 65 between a work rest 16 and presser foot 17.

The needle thread *a* is drawn from a convenient source through a thread-lock 18 and over take-up rolls 19 of any desired construction. Between the take-up and the 70 needle, the thread passes through a looper 20, and after being drawn through the work it is in position to be taken by a shuttle 21 and interlocked in the usual way with a shuttle thread.

The several instrumentalities hereinbefore mentioned are incidental to, but form no part of, the present invention.

The invention is embodied in a thread finger 25 which has the form of a hook on an 80 offset end of a round rod 26. The thread finger is adapted to engage the needle thread *a* between the looper 20 and the needle 14 as hereinafter explained. The rod 26 is mounted in two members 27 and 28 which 85 are respectively movable and stationary. The latter is in the form of a stud and is mounted on the frame 10 so as to be adapted to turn on its own axis. The rod 26 extends through and is adapted to slide in the 90 stud 28.

The movable member 27 is a stud through which the rod also extends, and to which it is adjustably clamped by means of a sleeve 29 and nut 30 threaded on the stud. The 95 stud and sleeve extend through a slot 31 in the frame and through the free end of an actuator or lever 32 in which they are loosely confined by the said nut and a shoulder 33 on the sleeve. The lever is fulcrumed 100 at 34 and has at its other end a cam roll 35 which occupies a cam groove 36 in a disk 37 mounted upon the power shaft 13. The rod 26 is reciprocated in the stud 28 by means of the actuator 32, and its irregularity of 105 movement due to the circular path of the stud 27 is neutralized by the revolute property of the stud 28. The simplicity of this

means of mounting the thread finger, and the consequent freedom and smoothness of movement will be apparent.

- The function of the thread finger, though not a part of the present invention, may be briefly stated as follows. Prior to insertion of the needle in the work, the thread finger occupies its forward position near the work as shown in Fig. 1. When the needle is passed through the work to the position shown in Fig. 2, the thread is released by the locking device at 18 and the thread finger is moved quickly to the rear, which position is shown by dotted lines in Fig. 1. The thread finger thus engages the thread in its hook and draws a predetermined quantity from the supply. The looper 20 is then actuated to lay the thread about the needle as shown in Figs. 2 and 3 after which the thread is locked again at 18. The needle then draws the loop of thread upwardly through the work, one side of the loop being fed by surplus thread in the take-up devices 19, and the other side by the now advancing thread finger. The thread finger may be adjusted forwardly or backwardly by bodily movement of the rod 26, and may be adjusted laterally by turning the rod about its own axis, a single nut 30 serving to set the clamping members for any position of the rod. A distinct advantage of so constructing the thread finger is that should the thread hook become worn or broken that end of the rod may be again bent so as to form a new hook, and this may be repeated so long as there is sufficient surplus in the length of the rod.

Having thus explained the nature of my said invention and described a way of constructing and using the same although without attempting to set forth all of the forms in which it may be made or all of the modes of its use, I declare that what I claim is:

1. The combination with a shoe sewing

machine having a looper, of an oscillatory arm, a pivoted member formed with a bearing, a rod extending through said pivoted member, said rod being bent at one end to form a hook adapted to engage the thread between the looper and the work and to measure a supply of thread, and a clamping device carried by said arm and adapted to clamp said rod at various points.

2. In a shoe sewing machine, the combination with a barbed needle, of an oscillatory arm, a pivot member supported and carried by said arm, a relatively stationary member, a rod engaging said pivot member and having sliding engagement with said stationary member, one end of said rod being bent to form a hook and adapted to engage the needle thread between the barb of the needle and the work, said rod being adapted to move longitudinally to draw the thread laterally; and means for clamping said rod to said pivot member.

3. In a shoe sewing machine, the combination with a barbed needle, of a bearing member, a rod bent at one end to form a hook, said hooked end being adapted to hook the needle thread between the barb of the needle and the work, and the other end of said rod being arranged to slide longitudinally in said bearing member, an oscillatory arm adapted to reciprocate said rod longitudinally, coactive clamping members pivotally mounted in said arm and adapted to clamp said rod, one of said clamping members being screw threaded, and a nut arranged on said threaded member, said clamping members being arranged to be tightened and secured in said arm by said nut.

In testimony whereof I have affixed my signature, in presence of two witnesses.

HARRIE A. BALLARD.
